UNITED STATES PATENT OFFICE.

HARRY FRANKEL, OF NEW YORK, N. Y., ASSIGNOR TO FRANKEL CONNECTOR COMPANY, INC., OF NEW YORK, N. Y., A CORPORATION OF NEW YORK.

ELECTRICAL CONNECTOR.

1,211,128.

Specification of Letters Patent. Patented Jan. 2, 1917.

Application filed April 20, 1916. Serial No. 92,445.

To all whom it may concern:

Be it known that I, HARRY FRANKEL, a citizen of the United States of America, residing at New York, N. Y., have invented 5 a new and useful Electrical Connector, of which the following is a specification.

My invention relates to an improved wire and terminal connector, the object being to provide a simple, effective and exceedingly strong and easily made and operated 10 device.

In the drawings: Figure 1 is a side elevation of my invention partly in section. Fig. 2 is an end elevation of one of the 15 parts. Fig. 3 is a perspective view of the parts separated.

In the drawings I have illustrated and shall describe herein my invention as applied to a connector of the kind applied to 20 a binding post in which the connector is provided with a forked arm 1 which it is designed to be secured to a binding post or screw-bolt 2. The connector proper comprises the body 3 which, as shown, is 25 threaded, and which is provided with a longitudinal central bore. The free end of the connector is tapered and is reduced in diameter, as at 4. The free end of said connector is likewise slotted longitudinally 30 to form short powerful gripping jaws. Screwing on to the body 3 is a collar 5 which has a screw thread extending partially through the same, the outer unthreaded end being internally reduced or tapered, 35 as indicated at 6 to engage the tapered end of the body 3.

7 represents a wire which in this instance, is provided with an insulating covering 8. This wire may be connected to the connector

by stripping a portion of the insulated covering from the end thereof and pushing the exposed end of the wire into the longitudinal bore of the body 3. The sleeve 5 may then be screwed up until the tapered portion 6 engages the tapered end of the connector body so as to draw the two sides thereof into intimate binding contact with the wire. The reduced portion 4 permits the gripping ends on opposite sides of the slit to yield more readily than if the sides 40 were of heavy stock throughout, and for that reason I prefer to provide this annular groove or reduced portion. By this simple means, I am enabled to electrically connect a wire with the terminal end very 45 quickly, and without the use of any special tools, and without the necessity of bending and thereby weakening the wire.

It is obvious that this connector may be employed in a wide variety of designs and 50 to that end it should be understood that I do not desire to limit myself to the particular form and arrangement of parts herein shown and described.

What I claim is:

A terminal connector comprising a 65 threaded body having a plurality of short gripping jaws extending longitudinally thereof at one end, and a longitudinal passage through said jaws into said body, an 70 annular groove around said connector at the outer end of said threaded portion and the inner end of said jaws, and a contracting member arranged to screw onto said threaded body and engage with and contract said 75 jaws.

HARRY FRANKEL.
